US0D1026882S

(12) **United States Design Patent** (10) **Patent No.:** **US D1,026,882 S**
(45) **Date of Patent:** **** May 14, 2024**

(54) **COMBINED PHONE AND PHONE CASE**

(71) Applicant: **Xiaoqing Chen**, Anhui (CN)

(72) Inventor: **Xiaoqing Chen**, Anhui (CN)

(**) Term: **15 Years**

(21) Appl. No.: **29/813,005**

(22) Filed: **Oct. 26, 2021**

(30) **Foreign Application Priority Data**

Jun. 1, 2021 (CN) 202130333710.7

(51) **LOC (14) Cl.** **14-03**

(52) **U.S. Cl.**

USPC ..... **D14/250**; D14/138 R

(58) **Field of Classification Search**

USPC D3/201, 218, 247, 249, 269, 327, 328;

D14/217, 248, 250-253, 432, 440, 142,

D14/144, 138 G, 138 R

CPC H04B 1/3888; H04M 1/0283;

H04M 1/0202; A45F 2005/028; A45F

2200/0525

Primary Examiner — L. A. Grabenstetter

(57) **CLAIM**

The ornamental design for a combined phone and phone case, as shown and described.

DESCRIPTION

FIG. 1 is a front perspective view of a combined phone and phone case showing my new design.

FIG. 2 is a rear perspective view of the combined phone and phone case.

FIG. 3 is a front view of the combined phone and phone case.

FIG. 4 is a rear view of the combined phone and phone case.

FIG. 5 is a left side view of the combined phone and phone case.

FIG. 6 is a right side view of the combined phone and phone case.

FIG. 7 is a top view of the combined phone and phone case; and,

FIG. 8 is a bottom view of the combined phone and phone case.

Any shading and cross-hatching are not features of the design but are utilized to illustrate the surface contours of the phone case design in the drawings.

1 Claim, 8 Drawing Sheets
